UNITED STATES PATENT OFFICE.

GERARD JOHN PHILLIPS AND LOUIS ANTHONY KELLER, OF LONDON, ENGLAND.

STOWING AND TRANSFERENCE OF BOATS ON BOARD SHIP.

1,239,821.

Specification of Letters Patent. Patented Sept. 11, 1917.

Application filed December 28, 1916. Serial No. 139,279.

To all whom it may concern:

Be it known that we, GERARD JOHN PHILLIPS and LOUIS ANTHONY KELLER, subjects of the King of Great Britain and Ireland, 5 residing, respectively, at London, England, have invented Improvements Relating to Stowing and Transference of Boats on Board Ship, of which the following is a specification.

10 This invention has reference to apparatus for enabling boats to be securely stowed side by side in rows athwartship and to be transferred successively to arrangements for lowering them over the side of the ship. In 15 such apparatus it has been proposed to provide a transversely arranged tilting frame provided with rails and to suspend the boats from trolleys running on an overhead rail that forms part of a cage in which the boats 20 are held and which is capable of being caused to travel along the rails of the tilting frame so that the cage will extend over the ship's side sufficiently to enable the boats to be lowered into the water by means of tackle 25 attached to the ends of the cage.

Now, in means according to the present invention, the rails of a transversely arranged tilting frame support rollers mounted at the stem and stern of each boat and 30 the boats, when stowed, are held at the desired distance apart by stops easily operable to release the boats and permit them to move under the action of gravity toward an independent davit arrangement by which 35 they are received from the frames and lowered over the side of the ship. In combination with the tilting frame which supports the boat trolleys there are provided side frames or chocks adapted to normally hold 40 the boats securely to the frame but adapted to be displaced so as to release the boats, for instance by means of a float or floats actuating the boat-holding side frames or 45 chocks in the event of the ship foundering. The boat holding side frames or chocks and the davit arrangements are preferably of the kind described in the specification of our former Letters Patent No. 1,210,530 dated 2 January 1917. The side frames or chocks 50 on the tilting frame are or may be arranged so as to be released by hand or other means, the actuating shafts of the boat chocks being linked or otherwise connected and acting either separately or as a whole.

55 The keel of each boat is or may be supported by a bar or frame more or less con-

forming to the stem, keel and stern of the boat and having forwardly and rearwardly projecting trunnions which rest upon suitable supports below the level of the boat 60 roller rail; the supports are slightly recessed in the middle to receive the trunnions and depressions or notches are formed alongside the trunnion supports, the arrangement being such that the boats being released 65 from their holding side frames or chocks and from the stops which engage the boat rollers, each boat will move along the rails, carrying its keel-supporting bar or frame with it until the trunnions of the latter drop 70 into the depressions or notches when the bar or frame will be left behind.

Figure 1 of the accompanying drawings is a side elevation of means according to this invention and Fig. 2 is a plan.

Fig. 3 is a detail view hereinafter referred to.

Fig. 4 is also a detail view hereinafter referred to illustrating a modification.

The tilting frame, which conveniently 80 comprises side girder-like members formed at the top as rails *a* and connected together at the bottom; the frame is mounted on pivots *b* at the center of its length and can be tilted so as to incline downwardly toward 85 either side of the ship; the tilting of the frame may be effected in any convenient manner, for instance by means of a screw *c* connected to the tilting frame by a link *d* and worked up or down by a worm-driven 90 nut *e* prevented from moving longitudinally of the screw.

Each bolt *f* has a roller *g* mounted at its stem and stern the rollers running on the rails *a* and being held by stops which may be 95 in the form of pairs of pins *h* attached to weighted levers *i* and projecting upwardly through holes in the rails *a* as shown. Lifting of the weighted levers withdraws the pins *h* and releases the boat.

On the inner side of each rail *a* is fixed a bar *k* formed with depressions or notches *l* as shown in Fig. 3 at each boat position the bar between each pair of depressions or notches *l* being slightly recessed at *m*; in the 105 recesses at *m* rest roller-like trunnions *n* of a bar *o* which serves to support the keel of the stowed boat throughout its length. Instead of the rollers of the keel supporting bar resting in recesses in the bar *k*, this bar 110 may be made with a flat between the depressions *l* and a pair of pins working in con-

junction with the pins h be arranged to hold the keel supporting bar in position until the boat is released. This arrangement is shown in Fig. 4, h^1 being the additional pins which 5 are attached to the plate carrying the pins h .

p, p are side frames or chocks of the kind described in the specification of our former Letters Patent No. 1,210,530 dated 2 January, 1917; these side frames or chocks are 10 pivoted to longitudinal members of the tilting frame and each set is provided with an actuating shaft q and releasing bell cranks r as described in said specification. To the end of each shaft q is fixed an arm s by 15 which the shaft can be turned and each arm s is connected through a pin and slot connection t with a sliding rod u ; this rod is coupled to a bell crank lever v one arm v^1 of which is curved and extends over an upwardly 20 extending rod w provided with a float x which, in the event of the vessel foundering, will move the rod w into contact with the arm v^1 and shift the sliding rod u to the left and, through the arms s , shafts q and cranks r , release the side frames 25 or chocks p of all the boats. The curve of the arm v^1 is struck from the center of the pivots b of the tilting frame so that assuming the parts are in the normal position shown, tilting of the frame will not prevent the float from properly actuating the side frame or chock releasing mechanism.

The weighted levers i to which the stop pins h are attached by links as shown can 35 be held in the positions corresponding to the raised and lowered positions of the stop pins by pins y that can be inserted in holes in the framing below the levers i to prevent the levers being lowered, or inserted in the 40 same holes above the said levers when such levers are lowered, to prevent the levers being raised. The levers i are fixed on shafts extending from side to side of the tilting frame each shaft having a lever at each end 45 the stop pins at the bow of a boat being attached to the one lever and those at the stern to the other.

As each boat arrives at the end of the rails, it is held by stop pins h^2 until the 50 davit tackle has been fixed, when the stop pins h^2 are lowered and the boat swung overboard on the davit tackle; the pins h^2 are required to prevent the boats prematurely leaving the tilting frame and their levers i 55 are not provided with pins y .

The end portions of the rails may extend beyond the main portion of the tilting frame and be inclined downwardly toward the sides of the ship.

60 Assuming it is desired to launch the boats, the tilting frame is inclined downwardly toward the desired side of the ship, say to-

ward the left side, by actuating the worm-driven nut e in the required direction. The boat nearest the left is then released from 65 its chocks p by actuating the lever s .

The lever i connected to the pins h which hold this boat is then actuated so as to lower these pins; the boat then travels on its rollers g down the rails a of the inclined 70 frame, the bar o moving with it until the bar trunnions n enter the lower notches m , when the bar will be held. The boat is held by the stop pins h^2 at the lower end of the tilted frame until swung out on the davit 75 tackle. Each succeeding boat is released in the same way.

If the ship founders, the chocks of all the boats will be released as soon as the water lifts the float x which then actuates the 80 lever v and then shifts the rod u and all the levers s of the chock releasing gear, leaving the boats free to float when the water reaches them.

What we claim is:—

1. Means for stowing boats on board ship comprising a frame adapted to be tilted toward either side of the ship and formed or provided with rails, wherein the rails serve as a track for rollers mounted at the 90 bow and stern of each boat, and stops are provided to hold the boats in their stowed positions on the supporting rails and adapted when released, to allow the boats to move along the rails toward independent davit 95 arrangements by which they can be lowered over the side of the ship, substantially as described.

2. In means for stowing boats on board ship according to claim 1, side frames or 100 chocks adapted to secure the boats to the tilting frame and to be displaced so as to release the boats by actuating means the side frames or chocks of the boats being operable separately or as a whole, substantially 105 as described.

3. In means for stowing boats on board ship according to claim 1 the combination with the track rails for the boat rollers, of supports at a lower level upon which rest 110 the trunnions of bars or frames each adapted to normally support the keel of the boat, the said trunnion supports being so shaped that as a boat moves along the rails, the keel supporting bar or frame will clear the keel 115 of the boat and be left behind, substantially as described.

Signed at London, England, this 8th day of December, 1916.

GERARD JOHN PHILLIPS.
LOUIS ANTHONY KELLER.
